Application June 21, 1937, Serial No. 149,286

24 Claims.

(Cl. 38—23)

This invention relates to improvements in pressing machines of the type generally used in laundries and particularly to a pressing machine having superposed upper and lower ironing units which coact so as to be simultaneously utilized by one operator.

An object of this invention is to provide a pressing machine having upper and lower ironing units, comprising a swingable upper ironing element, a fixed intermediate element and a swingable lower ironing element and automatic means for swinging the lower element forwardly and upwardly to a predetermined loading position when the upper ironing element is swung down into ironing position.

Another object of this invention is to provide a pressing machine having upper and lower ironing units, comprising a movable upper ironing element, a fixed intermediate element and a movable lower ironing element and automatic means for moving the lower element forwardly to a predetermined loading position in timed relation with the upper ironing element when said element is swung down into ironing position.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a front elevation of a pressing machine embodying my invention.

Figure 2 is an end elevation with one of the side frames removed.

Figure 3 is an end view of a modified pressing machine.

Figure 4 is a diagrammatic end view of the pressing machine with the upper pressing unit in an open position ready for loading.

Figure 5 is a diagrammatic end view of the pressing machine with the upper pressing unit in a closed position and the lower unit in an open position ready for loading.

In the illustrated embodiment of the invention, Figures 1 and 2 show a pressing machine of the type generally used in laundries, and comprising a closed-side frame 10 having uprights 11, 11 united rearwardly by a cross-head 12 which terminates in bearings 13, 13.

Levers 14 are fulcrumed on pins 15 in the bearings 13 and carry at one of their respective

ends an ironing element 16 having a polished ironing head 17. The opposite ends of the levers 14 have apertures 18 serving to receive and connect two elongated coil springs 19 with ears 20 extending from the frame 10. The frame 10 supports an ironing member or buck 21 having a work supporting upper padded surface or bed 22 which jointly with the head 17 forms an upper ironing unit 23. The buck 21 is fixed to the uprights 11 of the frame 10 in any suitable manner, such as by means of bolts 30.

The means for swinging the head 17 into and out of pressing engagement with the work supporting surface 22 consists of a cylinder and piston motor means 24, the piston rod 25 of which is connected to the lever 14 at a point 26.

Outward movement of the piston in the cylinder of the motor means 24 swings the head 17 downwardly about the pivot 15 into pressure engagement with the work supporting surface 22. This motion is accomplished by fluid pressure through a line 27, controlled by a hand operated control valve 28, shown in Figure 5, wherein the upper ironing unit 23 is shown in pressing position.

It is to be noted that the lower portion of the motor means 24 is pivotally secured at 70 to an angular lever 71 having a straight slot 72 and which is pivoted in a frame 74 on a pin 73. The frame 74 has curved slots 75 on opposite sides. The lower end of the arm 49 has a pivot 76 in engagement with the slot 75.

When the motor means 24 has motive fluid applied thereto the rod 25 moves upwardly until the head 17 is in pressing engagement with the bed 22. The cylinder 24 then moves downwardly with the angular lever 71 to a position shown in dotted lines carrying pivot 76 and arm 49 into lower position as shown in 77 and causing an increase leverage pressure against the bed 22 for ironing.

Movement of the head 17 out of pressing engagement with the work supporting surface 22 is accomplished when the fluid pressure is allowed to exhaust from the cylinder of the motor means 24 permitting the head 17 to be raised by the spring 19.

Fixed to the uprights 11 of the frame 10 by bolts 31 is an ironing element 32 having a polished ironing head 33. The head 33 may be in vertical alinement with the buck 21. An ironing element 35 having an upper pressing bed or work supporting padded surface 36 is slidably mounted in arcuate slots 37 in the frame uprights 11. The slots extend forwardly and upwardly to

a position considerably in front of the normal pressing position of the ironing head 33. The ironing element 35 has a lower plate 33 from both ends of which extend two circular projections 39 which are slidable in the slots 37 and by means of which the ironing element 35 may be moved to a position in alignment with the head 33. The padded supporting surface 36 and the head 33 jointly form a lower ironing unit 43.

Means for moving the ironing element 35 forwardly to a position well in front of the normal pressing position comprises levers 44 fulcrumed at their lower ends on pivots 45 in the uprights 11. The upper ends of the levers 44 have apertures 46 adapted to receive circular projections 47 extending from opposite ends of the plate 33 of the ironing element 35. The aperture 46 has a triangular upper end which permits contacting relation with the projecting member 47 both when the bed 36 is in registering relation with the head 33 or out of registering relation with said head, as shown in dot-and-dash lines in Figure 2.

Coil springs 48 mounted on the pivots 45 have their ends in engagement in any suitable manner (not shown) with the pivots 45 and the levers 44 respectively and serve to force the levers 44 forwardly.

In the position shown in Figure 2, the aperture 46 has a vertical wall which contacts the projection 47 and serves for moving the ironing member 35 in the direction of its forward and upward position shown in dot-and-dash lines.

Figures 2 and 4 show the upper pressing unit 23 in loading position and the lower pressing unit 43 in pressing position. The operator places an article to be ironed on the work supporting surface or bed 22 and actuates the valve 28 and admits motive fluid into the pipe 27 and the motor means 24. Actuation of the motor 24 causes the forward portion of the lever 14 to move down with the ironing head 17 and causes a gooseneck lever 49 connected to the ironing element 16 to swing forwardly at its lower end and to swing a pivotally connected lever 50 forwardly. The forward movement of the lever 50 actuates valve arm 51, link 52 and handle 57, which latter opens to exhaust, in valve mechanism 66, the fluid-pressure pipe from the motor means 53 and 54. This causes the ironing element 35 to drop due to its own weight to the bottom of the slot 37 and permits the springs 43, 48 to swing the arms 44 and the ironing element 35 forwardly and upwardly to the loading position shown in Figure 5.

Figure 5 shows the lower pressing unit 43 in loading position and the upper pressing unit 23 in pressing position. The operator places an article to be ironed on the work supporting surface or bed 33 and actuates a lever 55 on the control valve 28 and permits the motive fluid to exhaust from the pipe 27 and from the motor means 24. The springs 19 now pull down one end of the rotatable lever 14 and thereby raise the head 17 on the other end of said lever. The lever 49 is thereby moved rearwardly at its lower end, which arm 50 in turn swings the connected arm 59 rearwardly and actuates the arm 51. The latter moves link 52 to operate valve 66 which admits motive fluid into the motor means 54, causing the arms 44 to be swung rearwardly to move the lower ironing element 35 into alignment with the lower head 33. At the same time that arm 51 draws link 52 backward, arm 51 closes a valve mechanism (not shown) in the separate fluid pressure line leading to motor means 53. The 75

arms 44 have pivotally mounted pins 56 projecting outwardly therefrom and when the arms swing rearwardly, the pins 56 strike the last mentioned mechanism to open the same thereby causing motive fluid to enter into the motor means 53. The latter fills with said fluid and then begins to raise the ironing element 35, which has gotten into alignment with head 33 into pressing engagement therewith.

10 By disconnecting the arm 50 from the lever 49 it is possible to operate the upper and lower ironing units 23 and 43 separately and independently of each other. The upper ironing unit is then operated solely by the upper valve 28 and the lower ironing unit is then operated solely by the lower valve 66. For individual operation of the upper pressing unit 23 valves 89 and 61 are respectively operated. There is provided a hole in frame 11 matching a similar hole in arm 44 to provide for inserting a pin as shown at 83 to be inserted for locking the arms 44 against movement and holding the bed 36 away from the operator when not in use.

Figure 3 shows a modified pressing machine 25 having an upper ironing unit 60 and a lower ironing unit 43 in superposed relation in a frame 62 positioned on the outside of the frame 10. The upper ironing unit 60 comprises a fixed head 63 and a vertically movable bed 64 which is actuated up and down by a cylinder and piston motor means 65. The lower ironing unit 43 is identical with that shown in Figures 1 to 4 inclusive.

Many other modifications may be made in the 30 relative movements of the upper head and buck 35 and as well as the lower buck, but the lower head remains substantially stationary to accomplish the utility and purpose of the invention.

I claim:

1. A press comprising, in combination, an upper 40 pressing head, a lower buck, and intermediate means providing a fixedly positioned buck superimposed upon a fixedly positioned pressing head, frame means to carry all of said bucks and heads, means to move said lower buck between a position in pressing engagement with said intermediate pressing head and a position laterally displaced from said pressing position and elevated with respect thereto for the reception of work to be pressed, means to move said first-mentioned pressing head between a position in pressing engagement with said intermediate buck and a position sufficiently raised therefrom to clear said buck for the reception of work, and means to apply pressure between each of said movable elements and the fixedly positioned element with which it comes in contact.

2. A press comprising, in combination, a movable head, a movable buck, a fixedly positioned head, a fixedly positioned buck, frame means for supporting said heads and bucks, means for simultaneously moving said movable buck into contact with said fixedly positioned head and for moving said movable head out of contact with said fixedly positioned buck, and means for simultaneously moving said movable head into contact with said fixedly positioned buck and for moving said movable buck out of contact with said fixedly positioned head, said last-mentioned means being adapted for moving said movable buck laterally and upwardly to a work-receiving position elevated above the position of said buck when in pressing contact with said fixedly positioned head.

3. A duplex press comprising frame means, a plurality of bucks and a plurality of pressing heads supported by said frame means, one of said

bucks and one of said heads being fixedly mounted on said frame, one of said bucks and one of said heads being movably mounted on said frame, means for moving said bucks and heads into substantially vertical alignment, means for moving said movable buck to a position laterally displaced from said aligned position and elevated with respect to its position when in said aligned position, means for moving said movable head from its aligned position to a position laterally displaced and elevated therefrom, and means to create pressure between said movable buck and said fixed head and between said movable head and said fixed buck.

4. In a duplex press, in combination, frame means, a pressing head mounted on said frame rotatable about an axis all points of which are at a distance from the central longitudinal axis of said head, a buck below said head and fixedly positioned on said frame, means to move said head into and out of pressing engagement with said buck, said head being immovable while in said pressing engagement, a second pressing head fixedly positioned on said frame beneath said buck, a movable buck mounted on said frame, and means to move said movable buck between a position in pressing engagement with said second head and a position laterally displaced therefrom and elevated with respect thereto.

5. In a duplex press, in combination, frame means, a pressing head pivotally mounted on said frame, means for moving said head in an arcuate path about an axis all points of which are at a distance from the central longitudinal axis of said head, a buck fixedly positioned on said frame, means to move said head into and out of pressing engagement with said buck, means for holding said head in fixed position during its pressing operation, a second pressing head fixedly positioned on said frame beneath said buck, a movable buck mounted on said frame, and means to move said movable buck between a position in pressing engagement with said second head and a position laterally displaced therefrom and elevated with respect thereto.

6. In a duplex press, in combination, frame means, a pressing head pivotally mounted on said frame about an axis spaced from the center of said head, a buck fixedly positioned on said frame, means to move said head into and out of pressing engagement with said buck, said head being immovable while in said pressing engagement, a second pressing head fixedly positioned on said frame beneath said buck, a movable buck mounted on said frame, and means to move said movable buck between a position in pressing engagement with said second head and a position laterally displaced therefrom and elevated with respect thereto, and means connecting the means for moving said first-mentioned head and said means for moving said second-mentioned buck and requiring said first-mentioned head to be in pressing engagement with the first-mentioned buck when the second-mentioned buck is in work-receiving position removed from engagement with said second-mentioned head.

7. In a duplex press, in combination, frame means, a pressing head pivotally mounted on said frame about an axis spaced from the center of said head, a buck fixedly positioned on said frame, means to move said head into and out of pressing engagement with said buck, said head being immovable while in said pressing engagement, a second pressing head fixedly positioned on said frame beneath said buck, a movable buck mount-

ed on said frame, and means to move said movable buck between a position in pressing engagement with said second head and a position laterally displaced therefrom and elevated with respect thereto, the means for moving said second-mentioned buck comprising a pivotally mounted arm.

8. In a duplex press, in combination, frame means, a pressing head pivotally mounted on said frame, means for moving said head in an arcuate path about an axis which is spaced from the center of said head, a buck fixedly positioned on said frame, means to move said head into and out of pressing engagement with said buck, means for holding said head in fixed position during its pressing operation, a second pressing head fixedly positioned on said frame beneath said buck, a movable buck mounted on said frame, and means to move said movable buck between a position in pressing engagement with said second head and a position laterally displaced therefrom and elevated with respect thereto, the means for moving said second-mentioned buck comprising a pivotally mounted arm.

9. In a device of the character described, in combination, a frame, a movable head, a fixed buck, a fixed head and a movable buck all carried by said frame, means to move the movable head from an elevated position clearing the fixed buck for the reception of work to a pressing position in engagement with the fixed buck, said movable head being immovable while in said pressing position, means for moving the movable buck from a pressing position engaging the fixed head to a work-receiving position laterally displaced from the fixed head, and means for preventing both the movable head and the movable buck from being in pressing position at any predetermined time.

10. In a device of the character described, in combination, a frame, a movable head, a fixed buck, a fixed head and a movable buck all carried by said frame, means to move the movable head from an elevated position clearing the fixed buck for the reception of work to a pressing position in engagement with the fixed buck, means for holding said movable head in fixed position during its pressing operation, means for moving the movable buck from a pressing position engaging the fixed head to a work-receiving position laterally displaced from the fixed head, and means for preventing both the movable head and the movable buck from being in pressing position at any predetermined time.

11. In a duplex press comprising a movable pressing head, a fixed buck, a fixed pressing head, and a movable buck, means to move said movable head into and out of pressing engagement with said fixed buck, said movable head being immovable while in said pressing engagement, and means to move said movable buck from a position beneath said fixed head and in pressing engagement therewith to a position above the pressing surface of said fixed head and laterally displaced therefrom.

12. In a duplex press comprising a movable pressing head, a fixed buck having a surface positioned to support unaided an article to be pressed and to permit such supported article and said movable head to be pressed together, a fixed pressing head, and a movable buck having a surface positioned to support unaided an article to be pressed and to permit such supported article and said fixed head to be pressed together, means to move said movable head into and out of press-

ing engagement with said fixed buck, means for holding said movable head in fixed position during its pressing operation, and means to move said movable buck from a position beneath said fixed head and in pressing engagement therewith to a position above the pressing surface of said fixed head and laterally displaced therefrom.

13. In a duplex press comprising a movable pressing head, a fixed buck, a fixed pressing head, and a movable buck having a surface positioned to support unaidedly an article to be pressed and to permit such supported article and said fixed pressing head to be pressed together, means to move said movable head into and out of pressing engagement with said fixed buck, said movable head being immovable while in said pressing engagement, means to move said movable buck from a position beneath said fixed head and in pressing engagement therewith to a position above the pressing surface of said fixed head and laterally displaced therefrom, and means for simultaneously moving said movable head into pressing engagement with said fixed buck and said movable buck into spaced position with respect to said fixed head.

14. In a duplex press, in combination, frame means, a pressing head movably mounted on said frame, separate means providing a pressing surface fixedly positioned beneath said pressing head, separate means providing a heated pressing surface fixedly positioned beneath said first surface-providing means, both said surface-providing means being carried by said frame, a movable buck carried by said frame, means for moving said movable head into and out of engagement with said first-mentioned surface-providing means, and means for moving said movable buck between a position in engagement with said second surface-providing means and a position laterally displaced from and elevated with respect to the surface provided by said means.

15. In a device of the character described, in combination, a frame, a movable pressing head carried by said frame, a buck fixedly positioned on said frame, means to move said head out of pressing engagement with said buck, said head being immovable while in said pressing engagement, a second pressing head fixedly positioned on said frame beneath said buck, a second buck carried by said frame, means to move said second buck to a pressing position beneath said second head from a work-receiving position laterally displaced from said pressing position and elevated with respect to said pressing position, and means to operate the first and second-mentioned means simultaneously.

16. A press comprising, in combination, an upper pressing head, a lower buck, means intermediate between said upper head and said lower buck and providing a buck permanently and vertically above a pressing head, frame means to carry all said bucks and heads, means to move said lower buck between a position in pressing engagement with said intermediate pressing head and a position laterally displaced from said pressing position and elevated with respect to said pressing position for the reception of work to be pressed, means to move into pressing engagement the first-mentioned pressing head and the intermediate buck and to separate the first-mentioned pressing head and the intermediate buck sufficiently to permit the laying of work on the intermediate buck.

17. A press comprising, in combination, an upper pressing head, a lower buck, means inter-

mediate between said upper head and said lower buck and providing a buck permanently and vertically above a pressing head, frame means to carry all said bucks and heads, means to move said lower buck between a position in pressing engagement with said intermediate pressing head and a position laterally displaced from said pressing position and elevated with respect thereto for the reception of work to be pressed, means to move into pressing engagement the first-mentioned pressing head and the intermediate buck and to separate the first-mentioned pressing head and the intermediate buck sufficiently to permit the laying of work on the intermediate buck, and means for causing either pair of said bucks and heads to be in work-receiving position when the other buck and head are in pressing engagement.

18. A press comprising, in combination, an upper pressing head, a lower buck, means intermediate between said upper head and said lower buck and providing a buck permanently and vertically above a pressing head, frame means to carry all said bucks and heads, means to move said lower buck between a position in pressing engagement with said intermediate pressing head and a position laterally displaced from and with respect to the surface of said pressing head of said intermediate means for the reception of work to be pressed, and means to move into pressing engagement the first-mentioned pressing head and the intermediate buck and to separate the first-mentioned pressing head and the intermediate buck sufficiently to permit the laying of work on the intermediate buck.

19. A press comprising, in combination, an upper pressing head, a lower buck, means intermediate between said upper head and said lower buck and providing a buck permanently and vertically above a pressing head, frame means to carry all said bucks and heads, means to move said lower buck between a position in pressing engagement with said intermediate pressing head and a position laterally displaced from and with respect to the surface of said pressing head of said intermediate means for the reception of work to be pressed, said intermediate head being substantially immovable, and means to move into pressing engagement the first-mentioned pressing head and the intermediate buck and to separate the first-mentioned pressing head and the intermediate buck sufficiently to permit the laying of work on the intermediate buck.

20. A press comprising, in combination, an upper pressing head, a lower buck, means intermediate between said upper head and said lower buck and providing a buck permanently and vertically above a pressing head, frame means to carry all said bucks and heads, means to move said lower buck between a position in pressing engagement with said intermediate pressing head and a position laterally displaced from said pressing position and elevated with respect thereto for the reception of work to be pressed, means to move said intermediate buck into pressing engagement with said upper pressing head and to separate said intermediate buck and said upper pressing head sufficiently to permit the laying of work on said intermediate buck.

21. In combination, an uppermost pressing head element, a lowermost buck element, means for swinging one of said elements in an arc in a vertical plane whereby a garment to be pressed by the cooperation of said one element is freely exposed at one position of said one element, a unitary element having an upper buck surface and

a lower pressing head, means preventing said unitary element from being swung about any axis, means retaining said unitary element in a predetermined vertical plane, and means for moving predetermined ones of said elements whereby pressing engagement exists and ceases to exist between said head element and said buck surface and said pressing head and said buck element.

22. In combination, an uppermost pressing head element having a metallic pressing surface, a lowermost buck element having a padded article-receiving surface, means for swinging one of said elements in an arc in a vertical plane whereby a garment to be pressed by the cooperation of said one element is freely exposed at one position of said one element, a unitary element having an upper buck surface and a lower pressing head, means preventing said unitary element from being swung about any axis, means retaining said unitary element in a predetermined vertical plane, and means for moving predetermined ones of said elements until said head element and said buck surface are in engagement and said pressing head and said buck element are spaced from each other.

23. In combination, an uppermost pressing head element having a metallic pressing surface, a lowermost buck element having a padded article-receiving surface, means for swinging one of said elements in an arc in a vertical plane whereby a garment to be pressed by the cooperation of said one element is freely exposed at one position of said one element, a unitary element having an upper buck surface and a lower pressing head,

means preventing said unitary element from being swung about any axis, means retaining said unitary element in a predetermined vertical plane, and means for moving predetermined ones of said elements until said head element and said buck surface are spaced from each other and said pressing head and said buck element are in pressing engagement.

24. In combination, an uppermost pressing head element, a lowermost buck element having an article supporting surface, means for swinging one of said elements in an arc in a vertical plane whereby a garment to be pressed by the cooperation of said one element is freely exposed at one position of said one element, a unitary element having an upper buck surface and a lower pressing head, said supporting surface being positioned to support unaidedly an article to be pressed and to permit such supported article and said lower pressing head element to be pressed together, said buck surface being positioned to support unaidedly an article to be pressed and to permit such supported article and said uppermost pressing head element to be pressed together, means preventing said unitary element from being swung about any axis, means retaining said unitary element in a predetermined vertical plane, and means for substantially simultaneously producing pressing engagement between said head element and said buck surface and spacing said pressing head and said buck element, the means for moving said uppermost pressing head element being other than said lowermost buck element.

LEO M. KAHN.
